POWER COUPLING DEVICE

Filed Jan. 28, 1931

UNITED STATES PATENT OFFICE

ALSON R. SKINNER, OF COX CITY, OKLAHOMA

POWER COUPLING DEVICE

Application filed January 28, 1931. Serial No. 511,797.

This invention relates to an improved power coupling device.

It is an object of this invention to provide a safe and readily adjustable means of connecting the main driving mechanism with the pumping means for individual oil wells.

The invention will be fully understood from the following description taken in connection with the accompanying drawing in which latter—

Fig. 1 is a perspective view of the coupling device with parts broken away;

Fig. 2 is a perspective view of a sleeve constituting one of the elements of the coupling;

Fig. 3 is a perspective view of a tongue which is adapted to be adjustably disposed in the sleeve; and

Fig. 4 is a perspective view of a coupling pin.

Referring particularly to the drawing, the device comprises a fixed guideway in which the coupling proper is adapted to reciprocate. The fixed guideway includes cylindrical supports 1 and 2 which are fixed rigidly in abutments 3 of concrete or the like. The cylindrical supports 1 and 2 are provided with slots 4, 5 and 6 which are adapted to receive a housing 7. The housing 7 is recessed longitudinally to receive the coupling assembly for longitudinal reciprocating movement. A groove 8 is provided in the housing for a purpose to be later described. The portion 9 of support 1 opposite slot 4 constitutes an abutment against which one end of the housing 7 is adapted to be positioned. The abutment is provided with a horizontally disposed slot 11 for a purpose to be later described.

A coupling assembly is freely disposed in the guideway for longitudinal reciprocating movement. One portion of the coupling assembly includes a sleeve formed of spaced plates 13 and 14 and side bars 15. The sleeve is provided with an opening 16 at one end and at its opposite end it is attached to a spacer bar 17. Spacer bar 17 is removably inserted into the slotted end of a rod line 18 which is adapted to be connected to a suitable source of power, not shown, by means of which it is driven in reciprocatory move-

ment. A pin 19 detachably connects rod line 18 to spacer bar 17.

The coupling assembly includes also a tongue 22 which is adapted to be inserted through opening 11 in support 1 and through opening 16 in the sleeve. Tongue 22 is adapted to be connected to a suitable member to be actuated, such as a rod line, not shown, running to a well and which actuates a pump in the well.

In use, as for example in pumping an oil well, the device is assembled by inserting tongue 22 through the slot 11 in support 1 and maintaining it in position by means of a pin 23 which extends through one of suitable openings 24 spaced longitudinally of the tongue. Pin 23 is provided with a supporting shoulder 25 which is adapted to rest upon the tongue 22 and function as a bearing to engage the abutment 9 of support 1, and is provided with a shank 26 which is adapted to extend through openings 24 of tongue 22 and into the groove 8 previously mentioned. The tongue 22 is therefore held in position against the pull of the rod line which leads to the well.

The sleeve is then driven in longitudinal reciprocating movement in the guideway by eccentric operation of the power, and connection is made between the sleeve and tongue to lengthen or shorten the rod line which runs to the well. For accomplishing this result a slot 26 is provided in the sleeve of sufficient length to over-lap a plurality of the openings 24 and a pin 27 is adapted to be inserted into the slot 26 and a suitable opening 24. Preferably the pin 27 is inserted through slot 26 into a hole 24 which is nearest support 1 at the portion of the stroke of the sleeve when the sleeve is nearest support 1. During travel of the sleeve away from support 1 the tongue 22 is drawn farther into the guideway. During this stroke the pin 23 is removed and is reinserted into the opening 24 which is nearest the abutment at the time when the sleeve is farthest from support 1 and between the abutment 9 and the sleeve, whereby the tongue is held in its advanced position. The pin 27 can be withdrawn when the sleeve is farthest from support 1 and reinserted into slot 26 and

an opening 24 nearer support 1 upon reciprocation of the sleeve back to its first mentioned position. This operation can be repeated until the rod line which runs to the well has 5 been shortened the desired amount. The operation can be reversed to lengthen the rod line. Adjustment of the rod line is desirable also after breakage and repair of the rod line in order to pull up any slack in the rod 10 line. The holes 24 in tongue 22 extend oval longitudinally of the tongue and are slightly larger transversely also of the tongue than the pin 23, whereby insertion of the pin is 15 facilitated. The slot 26 is of such a length longitudinally of the sleeve as to permit the operative to have ample time to insert pin 27 in the desired opening 24. After the adjustment has been made the coupling assembly reciprocates in the guideway and functions to 20 transmit power.

Various changes may be made within the scope of the appended claims in which it is desired to claim all novelty inherent in the invention as broadly as the prior art permits.

25 I claim:

1. Means for transmitting reciprocating movement to a well pump, comprising a fixed guideway, a coupling assembly reciprocably disposed in the guideway, the assembly including a sleeve adapted to be connected to

a source of power, a tongue a portion of which projects into the sleeve and is adjustable longitudinally of the sleeve, the tongue having a plurality of longitudinally spaced openings, the sleeve having a slot aligned 76 with the openings and elongated to overlap a plurality of the openings, and a pin detachably engaging one of the openings and a portion only of the slot.

2. Means for transmitting reciprocating 75 movement to a well pump, comprising a fixed guideway, a coupling assembly reciprocably disposed in the guideway, the assembly including a sleeve adapted to be connected to a source of power, a tongue a portion of which projects into the sleeve and is adjustable longitudinally of the sleeve, the tongue having a plurality of longitudinally spaced openings, the sleeve having a slot aligned with the 80 openings and elongated to overlap a plurality of the openings, and a pin detachably engaging one of the openings and a portion only of the slot, the tongue having openings in the portion exteriorly of the sleeve, a fixed 85 abutment adjoining the last mentioned portion, and detachable means adapted to engage one of the openings and the side of the abutment facing the sleeve.
